UNITED STATES PATENT OFFICE.

JOHN LALLY, OF BOSTON, MASSACHUSETTS.

CLEANING AND STRAIGHTENING ROLLS.

1,230,584.

Specification of Letters Patent. Patented June 19, 1917.

Application filed February 20, 1917. Serial No. 128,820.

To all whom it may concern:

Be it known that I, JOHN LALLY, a citizen of the United States, residing at Boston, in the county of Suffolk and State of Massachusetts, have invented certain new and useful Improvements in Cleaning and Straightening Rolls, of which the following is a specification.

My invention relates to machines for 10 cleaning the outer surfaces of and straightening elongated objects of uniform cross section such as pipe, tubing or rod and my objects are the production of a simple, sturdy, long-lived machine which will automatically 15 perform these functions without requiring skilled labor for its operation and which will automatically free itself from any accumulation of dirt, etc., thereby preventing clogging.

20 In the drawing Figure 1 is a view of a pair of rolls with a pipe or tube therein; Fig. 2 a detail view, in section, of one roll; and Fig. 3 a side view of one half of a roll.

The machine comprises any suitable frame 25 (not shown). Each cleaning and straightening roll comprises a shaft 1, end plates 2, 2 mounted thereon with the cleaning and straightening disks 3, 3, separated by the spacing disks 4, 4 between them. The cleaning 30 disks 3, 3 are of various diameters and are so arranged that a line tangent to their peripheries will be approximately a portion of the cross-section of the object to be cleaned, the form shown being a semi-circle 35 for use in cleaning round pipe. The edges of the cleaning disks 3, 3 are preferably, although not necessarily, sharpened as shown in Fig. 2 and the spacing disks 4, 4 are of less diameter than the adjacent cleaning disks so 40 that scale, dirt and dust will fall out between the cleaning disks and the machine will not clog.

The end plates, cleaning disks and spacing 45 disks are drilled at 5, 5 and the tie-bolts 6, 6 are run through to bind the disks and end plates solidly together. All the disks and end plates are preferably keyed to the shaft at 8.

In the machine a pair of rolls are mounted 50 one over the other as shown in Fig. 1. When the two are rotated the pipe 9 is fed through

and the edges of the cleaning disks 3, 3 cut and grind away the outer surface scale and dirt and any inequalities are at the same time smoothed out and the pipe straightened.

55

If desired but one roll may be used for cleaning purposes only and the pipe twisted by hand or by any suitable device as it feeds through thus removing scale and dirt.

One of the rolls may be rotated by power 60 and the frictional engagement of the other roll with the pipe relied upon to rotate it as the pipe travels through.

If articles (such as square columns) other than pipe or tubing are to be cleaned or 65 straightened the cleaning disks are so arranged that a line tangent to the peripheries will be approximately a portion of the cross-section of the article being operated upon.

By using thin cleaning disks and spacing 70 disks an infinite number of cross-sections may be ground by proper assemblage.

I claim:

1. A cleaning roll comprising a plurality of disks of various diameters spaced one 75 from the other and secured together so that a line tangent to their peripheries will be approximately a portion of the cross-section of the object to be operated upon.

2. A cleaning roll comprising a plurality 80 of cleaning disks of various diameters, spacing disks between them of lesser diameters than the adjacent cleaning disks, so that a line tangent to the peripheries of the cleaning disks will be approximately a portion of 85 the cross-section of the object to be operated upon, end plates and means for tying the end plates, cleaning disks and spacing disks together.

3. In a cleaning roll the combination of a 90 shaft, a plurality of cleaning disks of various diameters secured thereon, spacing disks of less diameter than the adjacent cleaning disks separating the latter, end plates and tie bolts extending through the 95 end plates, cleaning disks and spacing disks, a line tangent to the peripheries of the cleaning disks being approximately the cross section of a portion of the object to be operated upon.

4. In a cleaning and straightening machine, a pair of rolls located adjacent to one 100

another each comprising a plurality of cleaning disks of various diameters spaced one from another, means for securing them together, a line tangent to the peripheries of the two sets of disks at their opposition being approximately the cross-section of the object to be operated upon.

In testimony whereof I have affixed my signature in the presence of two witnesses.

JOHN LALLY.
